UNITED STATES PATENT OFFICE.

JULIA A. WRIGHT, OF AUSTIN, ILLINOIS.

DESIGN FOR A DRESSMAKER'S PATTERN-CHART.

SPECIFICATION forming part of Design No. 30,553, dated April 11, 1899.

Application filed February 27, 1899. Serial No. 707,110. Term of patent 7 years.

To all whom it may concern:

Be it known that I, JULIA A. WRIGHT, a citizen of the United States, and a resident of Austin, county of Cook, State of Illinois, have 5 invented and produced a new and useful Design for a Dressmaker's Pattern-Chart, of which the following is a description, reference being had to the accompanying drawings, which form a part of this application, and in 10 which—

Figure 1 is a plan view showing the contour of my design, and Fig. 2 is a front edge view of the same.

Reference being had to the drawings, it will 15 be seen that my design is a flat figure having an irregular contour made up of a series of curved and straight lines, which may be described as follows: From the point marked 1 in the upper right-hand corner of the pattern 20 and extending downwardly to the point marked 2 is a long slightly - curved line. Meeting the point 1 and extending from the point 3 at the upper left-hand corner is a compound - curved line which extends approxi- 25 mately at right angles to the line 1 2 and may be designated as the "shoulder-curve" line of my pattern. From the point 3 to the point 4 is a downwardly-extending straight line at right angles to the line 3 1, and from said

point 4 extends a short horizontal line to the 30 right at right angles to the line 4 3. From the end of this short line a curved line extends upwardly and to the left to the point 4^a, from which another curved line is described downwardly and to the right to the 35 point 5. Forming an obtuse angle at the point 5 extends a long curved line to the right to the point 6 at the lower left-hand corner of the pattern. From the point 6 and forming an obtuse angle with the line 5 6 is a 40 downwardly - extending and deeply - curved line which extends to the bottom of the figure and then rises to the point 2, thus completing the pattern design.

In general outline the design resembles 45 somewhat the figure 7.

Having thus described my design, what I claim as new, and desire to secure by Letters Patent, is—

The design for a dressmaker's pattern-chart, 50 substantially as shown and described.

In testimony whereof I affix my signature in presence of two witnesses.

JULIA A. WRIGHT.
